UNITED STATES PATENT OFFICE.

EDWARD M. LOCKWOOD, OF PHILADELPHIA, PENNSYLVANIA, ASSIGNOR TO C. R. CARVER
COMPANY, A CORPORATION OF NEW JERSEY.

INKING MECHANISM FOR PRINTING-MACHINES.

No. 921,615.

Specification of Letters Patent. Patented May 11, 1909.

Original application filed June 17, 1907, Serial No. 379,385. Divided and this application filed October 3, 1907.
Serial No. 395,785.

To all whom it may concern:

Be it known that I, EDWARD M. LOCKWOOD, of the city and county of Philadelphia and State of Pennsylvania, have invented an Improvement in Inking Mechanism for Printing-Machines, of which the following is a specification.

My invention has reference to inking mechanism for printing machines, and consists of certain improvements which are fully set forth in the following specification, and shown in the accompanying drawings, which form a part thereof.

This invention may be employed in connection with printing presses generally but is more particularly useful in that type of embossing and printing press set out in my application Serial No. 379,385 and filed June 17, 1907, of which this application is a division.

The object of my invention is to provide an adjustable inking roller which shall have yielding means of support for regulating the coaction of the roller with the ink supplying roller and die or type to be printed from.

My invention consists of an inking roller combined with means for giving to it a reciprocating movement over the carriage and the die or type thereon, spring controlled devices for pressing the inking roller toward the die or type, and hand controlled devices for regulating the spring controlled devices whereby the roller may be adjusted normally to vary its elevation with respect to the carriage upon which the die or type is clamped.

My invention also embodies details of construction which, together with the features above specified, will be better understood by reference to the drawings, in which:

Figure 1 is a side elevation of an embossing and printing press embodying my improvements; Fig. 2 is an elevation of the ink applying roller and its supporting devices; Fig. 3 is a side elevation of the same; Fig. 4 is a sectional elevation of a portion of the same; and Figs. 5 and 6 are plan views of details of the same.

2 is the main frame of the press, 3 are the guides for the reciprocating carriage 4, which carries the embossing and printing die or type. This carriage is reciprocated in its guides by links 6 and 7, jointed at 8.

The link 6 is connected to the rocking lever 5, which is rocked by link 81, rocker arm 80 and rock shaft 79, the latter being rocked by arm 89 and connecting rod 88 which receives its reciprocating motion from a crank wheel 86 and power shaft 21. The hinge 60 between the parts 6 and 7 is provided with a guide roller 8 which travels in guides 9 and 10 in the main frame and gives to the carriage a dwell in its motion when it reaches the printing position.

13 is the embossing plunger and is intended to carry the die to give the impression in the act of embossing and printing, and may be reciprocated in any suitable manner.

When the carriage 4 with the die clamp thereon is moved backward, the ink is applied to the surface of the die by means of the ink applying roller 31 which is preferably made with a plush surface, so that the ink may enter the recesses in the die. This ink applying roller receives the ink from a rotating ink roller 30 revolving in an ink well, it being driven by means of a sprocket wheel 67 and a sprocket chain 66 receiving power from a sprocket wheel 65 on the driving shaft 64, as shown in Fig. 1. The ink applying roller 31 is flexibly carried on the upper end of the rocker arms 32, and these are rocked by links 33, bell cranks 34, rod 35, and cam 36 which is secured to the cam shaft 21. This cam is so timed as to its action that the ink applying roller 31 has been moved forward and held stationary at the time the carriage 4 is being moved backward and forward under it.

Referring now to the means for flexibly supporting the inking roller 31, I will refer more specifically to Figs. 2 to 6. The shaft 102 is loosely journaled in the ends of the rocking arms 32. Secured to this shaft 102 is an arm 103 having a hole near its end. Extending through this hole is a screw-threaded rod 105 which screws into a pivoted nut 32^a on one of the arms 32. Rod 105 is provided with a rigid collar 106 against which the arm 103 rests and upon which it is spring pressed by a coiled spring 104 on the upper extension of the screw-threaded rod 105. By turning the rod 105 it is screwed into the nut 32^a and therefore will cause the shaft 102 to take different positions of adjustment. To lock the rod 105

against accidental unscrewing, I provide a collar 107 having one or more teeth 107^a which may engage one or more of the recesses 108 on the arm 103. The collar furthermore is carried on the rod by a spline connection, so that it does not turn on the rod, but will rotate with it and has capacity for longitudinal adjustment.

Secured to the shaft 102 are arms 117, and these arms are each provided with lateral projecting pins 117^a. Loosely sleeved upon the shaft 102 are two bearings 109 which are provided with transverse apertures 114 into which the lateral pins 117^a extend with freedom of considerable motion (Fig. 4). Plungers 115 carried by the bearings 109 are spring pressed upward by springs 116 so as to make a spring support against downward thrust by the pins 117^a. The bearings 109 have notches 110 for receiving the ends of the shaft 31^a carrying the inking roller 31. The shaft 31^a is locked in position in the bearings 109 by spring bolts 111 which are pressed downward by coiled springs 112. A hand nut 113 is secured to the upper end of each bolt for raising it against the action of the spring when releasing the shaft. Pins 113^a are secured to the nuts 113 so that when the bolts are fully raised and slightly turned, they are held in such elevated position as will permit the shaft to be readily withdrawn. Furthermore, when the bolts are in locking position, the pins 113^a are received in grooves 113^b which prevent the bolts from turning and thereby maintain the flat side of the bolts presented to the shaft 31^a, as will be readily understood from Fig. 4. It will now be understood that if a pressure is applied to the roller 31 upward, the bearings 109 will rock upon the shaft 102 and this upward movement will be resisted by the coiled springs 116 so that the inking roller 31 will be elastically supported, and hence will be caused to follow any level or irregularity in the surface of the die to which it is applying ink. Moreover, the normal level of this inking roller is readily adjusted by the screw rod 105 which adjusts the shaft 102 and thereby changes the normal position of the bearings 109 with relation to the level of the die carriage. Wheels 118 may be secured to the shaft 31^a for the purpose of engaging the wheels 11^a on the side of the die clamp 11 of the carriage 4 so that the inking roller 31 will be elevated until it gets over the rear end of the die clamp and will then be lowered into inking contact with the die, and again elevated out of contact with the forward part of the die clamp, and vice versa. In this way, the ink is thoroughly applied to the die and not to any other part of the machine. The flexible supporting of the inking roller combined with the means for relatively adjusting its distance with re-

spect to the die carrying carriage which I have here shown and described is exceedingly effective, but it is evident that the particular adjustments involved may be secured in many other modified forms of apparatus. 70

While I have shown the details of construction which I have preferred and employed in the commercial form of press embodying my improvements, I do not confine myself to these specific details, as it is evident to one skilled in the art that the same general adjustments may be accomplished by other forms of the said details without departing from the spirit of the invention involved in them. 75

Having now described my invention, what I claim as new, and desire to secure by Letters Patent, is:—

1. In an embossing and printing press, the reciprocating die carriage, combined with an ink supplying device, an inking roll for transferring ink from the ink supplying device to the die, bearings in which the inking roll is journaled, a transverse shaft parallel to the inking roll and upon which the bearings are loosely hinged, a spring connection between the bearings and shaft whereby the inking roller is spring pressed toward the die carriage when applying ink, and power devices for reciprocating the transverse shaft 90 to and from the reciprocating carriage.

2. In an embossing and printing press, the reciprocating die carriage combined with an ink supplying device, an inking roll for transferring ink from the ink supplying device to the die, bearings in which the inking roll is journaled, a transverse shaft parallel to the inking roll and upon which the bearings are loosely hinged, a spring connection between the bearings and shaft whereby the inking roller is spring pressed toward the die carriage when applying ink, rocker arms 100 for carrying the shaft, hand adjusting devices for adjusting the shaft about its axis and locking it in its adjusted position upon 105 the rocker arms, and power devices for reciprocating the rocker arms and carrying the transverse shaft to and from the reciprocating carriage.

3. In an embossing and printing press, a reciprocating die carriage, with a reciprocating ink applying roll, and means for supporting the roll consisting of a reciprocating shaft, bearings in which the roll is loosely journaled, arms secured to the shaft having 120 lateral portions, spring actuated plungers carried by the bearings and pressing against the lateral portions of the arms, and means for reciprocating the shaft.

4. In an embossing and printing press, a reciprocating die carriage, with a reciprocating ink applying roll, and means for supporting the roll consisting of a reciprocating shaft, bearings in which the roll is loosely journaled, arms secured to the shaft having 130

lateral portions, spring actuated plungers carried by the bearings and pressing against the lateral portions of the arms, means for reciprocating the shaft, and means for adjusting the shaft rotatably about its axis upon the reciprocating means.

5 5. In an embossing and printing press, a reciprocating die carriage, with a reciprocating ink applying roll, and means for supporting the roll consisting of a reciprocating shaft, bearings in which the roll is loosely journaled carried by the shaft, rocker arms 10 32 for operating the shaft, an arm 103 secured to the shaft for adjusting it on the 15 rocker arms, a screw rod 105 between one of the rocker arms and the arm 103 for adjusting the latter, and a spring locking device for holding the screw rod in its adjusted position.

20 6. In an embossing and printing press, a reciprocating die carriage, with a recipro-

cating ink applying roll, and means for supporting the roll consisting of a reciprocating shaft, bearings in which the roll is loosely journaled carried by the shaft, rocker arms 25 32 for operating the shaft, an arm 103 secured to the shaft for adjusting it on the rocker arms, a screw rod 105 between one of the rocker arms and the arm 103 for adjusting the latter, and a spring locking device 30 for holding the screw rod in its adjusted position consisting of a toothed washer 107 adapted to engage an irregular surface of the arm 103 and held upon the rod 107, and a coil spring 104 about the rod for forcing 35 the washer into engagement with the arm 103.

In testimony of which invention, I have hereunto set my hand.
